UNITED STATES PATENT OFFICE.

JOHAN GUSTAF RICHERT, OF GOTHENBURG, SWEDEN.

DEVICE FOR CUSHIONING THE SHOCK IN WATER-PIPES BY AUTOMATIC COCKS.

SPECIFICATION forming part of Letters Patent No. 360,326, dated March 29, 1887.

Application filed June 11, 1886. Serial No. 204,850. (No model.) Patented in Sweden September 9, 1885, No. 245; in France September 22, 1885, No. 171,291; in Denmark September 24, 1885; in Austria-Hungary September 26, 1885, No. 34,994; in Germany September 26, 1885, No. 34,876; in Belgium September 28, 1885, No. 70,321; in England September 29, 1885, No. 11,610, and in Norway December 31, 1885, No. 470.

To all whom it may concern:

Be it known that I, JOHAN GUSTAF RICHERT, a subject of the King of Sweden, and a resident of Gothenburg, in the Kingdom of Sweden, 5 have invented certain new and useful Improvements in Devices for Cushioning the Shock in Water-Pipes by Automatic Cocks, (for which I have obtained patents in the following countries, to wit: Sweden, No. 245, dated September 9, 1885; France, No. 171,291, dated September 22, 1885; Denmark, dated September 24, 1885; Austria-Hungary No. 34,994, dated September 26, 1885; Germany, No. 34,876, dated September 26, 1885; Belgium, No. 70,321, dated 10 September 28, 1885; England, No. 11,610, dated September 29, 1885, and Norway, No. 470, dated December 31, 1885;) and I do hereby declare that the following is a full, clear, and exact description of the invention, which will enable others skilled in the art to which it 15 pertains to make and use the same, reference being had to the accompanying drawings, which form a part of this specification, and in which—

25 Figure 1 is a vertical sectional view of a portion of a water-closet, showing my improved device applied. Fig. 2 is a vertical sectional view of the device. Figs. 3 and 4 are similar views illustrating modified forms of the device. Fig. 5 is a vertical sectional view illustrating another modification. Fig. 6 is a horizontal sectional view of the device shown in Fig. 5 on the line *xx*; and Fig. 7, 8, and 9 are, respectively, a front view, a side elevation, and 30 a top view of the same.

35 Similar letters of reference indicate corresponding parts in all the figures.

My invention has relation to devices for cushioning the shock in water-pipes caused 40 by the sudden closing of automatic cocks as usually employed in water-closets, supply-tanks, feeding-reservoirs, flushing-cisterns, and in many other cases where the service-pipes or discharge-pipes leading from the tank 45 or reservoir are provided with automatic or self-closing cocks. The sudden closing of these automatic cocks creates a certain shock or concussion, which affects the pipes injuriously, as it is apt to cause leakage as well as

waste; and the object of my device is to overcome this sudden shock or concussion caused by the rapid closing of the automatic cock, and this I accomplish by cushioning the shock as the cock is closed, substantially as will be hereinafter more fully described.

55 In the accompanying drawings, the letter A indicates a tank or receiver, which has the service-pipe B entering at one side, while the delivery-pipe C, which is provided with a cock or faucet, D, opens through the other wall of 60 the receiver, said pipe C being provided with a flaring or funnel-shaped inner end, which projects over and around the inner end of the inlet-pipe B.

65 The upper portion of the tank or receiver above the pipes B and C may be bulb-shaped, as shown at E in Fig. 2, or of any other desired configuration, as shown on the drawings. Referring to the construction shown in Fig. 2, which is the construction I prefer to use for 70 ordinary tap-cocks and not for water-closets, it will be seen that the lower contracted portion of the tank or receiver A is provided with a perforated partition, F, which separates the main body of the tank from the valve-chamber G, the bottom of which is provided with a valve seat or aperture, H, over which fits a ball-valve, I, preferably consisting of a ball of any suitable heavy material having a rubber or other similar elastic covering.

75 It will be seen that the pressure of the water, partially filling the tank as it enters through the inlet-pipe B, will force the valve against its seat, so as to close the aperture H and compress the air contained in the upper portion, E, of the tank, so that when the cock of the outlet-pipe or discharge-pipe C is opened the water passing from the inlet-pipe B into the flaring inner end of pipe C will cause the latter to operate in precisely the same manner as 80 an injector, sucking the water out of the tank A and valve-chamber G, so as to draw the water out of the tank.

85 It is obvious that the device shown in Fig. 2 will operate in precisely the same manner if 90 its upper portion, E, is made cylindrical and of the same dimensions as the valve-chamber G, my only reason for making this upper por-

tion bulb-shaped being to increase the capacity of the air-chamber. In some cases it is not convenient or expedient to make the upper part, E, bulb-shaped, and this part may be 5 constructed in a very simple and inexpensive manner from a section of ordinary pipe closed at the top.

It will be seen that as the water rushes out of the receiver through pipe C, as above stated, 10 the ball-valve I will be lifted from its seat, thereby admitting air into the tank through the aperture H; but the moment pipe C is closed the water entering the tank through pipe B will again partly fill the tank, close the 15 valve, and expend its shock upon the inclosed body of air, which thus operates to cushion the shock and prevent it from spreading and being communicated to the pipes.

In Figs. 3 and 4 of the drawings I have 20 shown the modification which I consider most suitable for water-closets and similar purposes. By reference to the said figures it will be seen that the valve-chamber is placed at the upper end of the tank, and the ball-valve is in this 25 case a light floating ball, which may be forced up against the valve-seat by the water rising in a tube, J, which projects from the valve-chamber down into the body of the tank, and through which tube the water is forced upward by the air being compressed within the 30 tank.

In Fig. 3 the valve-chamber is provided at its upper end with a curved tube, J', which will admit air and prevent impurities from 35 entering, while in Fig. 4 the valve-chamber is provided with a partition, K, which has an aperture opening into a chamber, L, provided at one side with an aperture and curved air-tube, M. Both these devices operate in precisely the same manner.

In Fig. 5 is shown a vertical sectional view of still another modification, a horizontal sectional view of the same being shown in Fig. 6, a front view in Fig. 7, a side elevation in 45 Fig. 8, and a plan or top view in Fig. 9. In this modification of my device the floating ball-valve is confined within a valve-chamber at the lower end of a box, O, which is inserted through the top of the tank A, its upper projecting part being provided with an air-inlet, M. The inlet-pipe B passes transversely through the tank, entering the same at one end, passing out at the other end, and having at its middle, inside the tank, a projecting 50 nozzle, B', which projects into the flaring mouth of the delivery-pipe C. This construction will be found advantageous where it is desired to continue the flow of water through pipe B—as, for example, where a number 55 of these devices are connected or combined in a continuous system.

In Fig. 1 I have shown one method of connecting the tank or receiver A to the bowl of a water-closet and to the service-pipe, and from what has already been stated the operation of the device in this connection will require no further explanation.

Having thus described my invention, I claim and desire to secure by Letters Patent of the United States—

1. In a device for cushioning the shock in high-pressure water-service pipes caused by closing the cocks, the combination of a receiver provided with an inwardly-opening valve, an outlet-pipe having an outwardly-flaring inner 75 end, and an inlet-pipe entering the flaring portion of said outlet-pipe, as and for the purpose set forth.

2. In a device for cushioning the shock in high-pressure water-service pipes caused by 80 closing the cocks, the combination of a receiver, an inlet-pipe entering the receiver at one side, an outlet-pipe having a flaring inner end fitting around the inner end of the inlet-pipe and passing out through the opposite side of 85 the receiver, a valve-chamber communicating with the lower portion of the receiver and having a valve-aperture opening to the outside, and a ball-valve fitting upon the inner side of the valve-aperture and adapted to be 90 forced against the same by the pressure from within, as and for the purpose shown and set forth.

3. In a device for cushioning the shock in high-pressure water-service pipes caused by 95 closing the cocks, the combination of a receiver having a valve-aperture in the lower end, a heavy ball-valve fitting upon the valve-aperture, an inlet-pipe entering the lower portion of the receiver, and an outlet-pipe having a 100 flaring inner end fitting around the inner end of the inlet-pipe and projecting out through the opposite side of the receiver, as and for the purpose shown and set forth.

4. In a device for cushioning the shock in 105 high-pressure water-service pipes caused by closing the cocks, the combination, with a receiver provided with inlet and outlet pipes, of a valve-chamber located above said receiver and provided with a valve-aperture at its top, 110 a tube projecting downwardly from said chamber, and a floating ball-valve for closing said aperture, substantially as set forth.

In testimony that I claim the foregoing as my own I have hereunto affixed my signature 115 in presence of two witnesses.

JOHAN GUSTAF RICHERT.
